UNITED STATES PATENT OFFICE.

SIMON E. HOFEN, OF DACOMA, OKLAHOMA, ASSIGNOR OF ONE-HALF TO JAMES R. BAXTER, OF HOPETON, OKLAHOMA.

TWO-ROW LISTER.

1,333,312.

Specification of Letters Patent.

Patented Mar. 9, 1920.

Application filed June 16, 1919. Serial No. 304,374.

To all whom it may concern:

Be it known that I, SIMON E. HOFEN, a citizen of the United States, residing at Dacoma, in the county of Woods and State 5 of Oklahoma, have invented certain new and useful Improvements in Two-Row Listers, of which the following is a specification, reference being had to the accompanying drawings.

10 This invention relates to the art of farming implements, and particularly to an improved two-row lister, especially adapted for attachment to the rear of a tractor, and one of the objects of the invention is to 15 provide means for connecting a beam structure adjustably to the frame of the lister, whereby the beam structure may be adjusted relatively to the lister frame and vice versa, in order to adjust the listers in dif- 20 ferent positions relatively to the soil.

A further object of the invention is the provision of a beam structure comprising a hollow tubular connector rectangular in cross-section adjustably connected to the 25 lister frame and pivotally mounted between a pair of braces, so that the rear end of the connector may be adjusted relatively to the lister frame on its pivot, so that the forward end of the connector may accommo- 30 date itself and be connected to tractor frames of different heights, and also whereby the listers may accommodate themselves to the irregularities of the ground or soil.

While the design and construction at 35 present illustrated and set forth is deemed preferable, it is obvious that as a result of a reduction of the invention to a more practical form for commercial purposes, the invention may be susceptible to changes, and 40 the right to these changes is claimed, provided they are comprehended within the scope of what is claimed.

The invention comprises further features and combination of parts, as hereinafter set 45 forth, shown in the drawings and claimed.

In the drawings:

Figure 1 is a plan view of the improved two-row lister constructed in accordance with the invention, showing the connection 50 between the connector and the lister frame, and also showing the braces.

Fig. 2 is a sectional view on line 2—2 of Fig. 1.

Fig. 3 is a sectional view showing the 55 connector, the clevis, and the lister in ele-

vation and also showing the connector adjusted, relatively to the lister frame.

Referring more especially to the drawings, 1 designates a conventional form of lister frame, to which the beams of the 60 listers are connected, as shown at 2. Said lister beams are provided with the usual and conventional form of listers 3. Secured as at 4 to the forward rail of the lister frame is a plate 5, provided with forwardly 65 extending spaced arms 6. A hollow tubular connector 7 is provided, and in one end of which a projecting arm 8 of a clevis member 9 is secured by means of the bolts 10. The spaced arms 6 engage on opposite 70 sides of the clevis 9, there being a bolt 11 passing through the spaced arms 6 and through any one of the apertures 12 of the clevis 9, so that by removing the bolt 11, and adjusting the same in any of the apertures 12 of the clevis, the rear end of the connector may be adjusted relatively to the lister frame and vice versa. A pair of diverging brace irons 13 is provided. Forward angularly bent ears 14 of the brace 80 irons are secured to the connector by means of the transverse bolt 15, which is provided with the usual nut, so that the connector may move pivotally on the bolt. The clevis 9 is arcuately curved, concentric with the 85 bolt 15, so as to permit the connector to be adjusted, and by adjusting the connector, it will be seen that the lister frame is capable of moving pivotally relatively to the connector, so that the listers of the lister frame 90 may automatically adjust and accommodate themselves to the irregularities of the ground or soil. The outer ends of the brace irons have portions 16, which extend rearwardly and are bolted to the end portions 95 of the lister frame, as shown at 17, whereby the lister frame is capable of movement. Secured in the forward end of the connector as shown at 18 is a connecting strip or plate 19 having an opening or aperture 20, for 100 the reception of a pin (not shown) of a clevis (not shown), whereby the two-row lister may be connected to a tractor (not shown), so that the lister may be drawn over the ground or soil.

The invention having been set forth, what is claimed as new and useful is:

1. The combination with a lister frame provided with a pair of listers, of a hollow tubular connector to be pivoted to a tractor, 110

and in turn having its rear end provided with a clevis connection with the lister frame, a pair of braces, a single transverse bolt connecting the forward ends of the braces to the connector, said braces diverging rearwardly and having their rear ends secured to the ends of the lister frame.

2. The combination with a lister frame provided with a pair of listers, of a hollow tubular connector to be pivoted to a tractor, and in turn having its rear end provided with a clevis connection with the lister frame, a pair of braces, a single transverse bolt connecting the forward ends of the braces to the connector, said braces diverging rearwardly and having their rear ends secured to the ends of the lister frame, said clevis connection comprising an arcuate

clevis concentric with the single securing bolt of the braces and provided with a plurality of apertures, said clevis having an extension extending into the rear end of the connector, means to secure the extension in the connector, and a plate secured to the lister frame and provided with spaced arms extending forwardly, and means passing through the arms and through any one of the apertures for adjustably connecting the clevis between the arms.

In testimony whereof I hereunto affix my signature in the presence of two witnesses.

SIMON E. HOFEN.

Witnesses:

PAUL FENNESSEY,
G. L. McCLOURE.
